UNITED STATES PATENT OFFICE.

DEAN E. LOCHMAN, OF BELMONT, MASSACHUSETTS, ASSIGNOR TO BLUE TIP PILE WIRE & KNIFE COMPANY, OF BEDFORD, MASSACHUSETTS, A CORPORATION OF MASSACHUSETTS.

FILE-WIRE KNIFE.

Application filed August 18, 1925. Serial No. 50,965.

To all whom it may concern:

Be it known that I, DEAN E. LOCHMAN, a citizen of the United States, and a resident of Belmont, in the county of Middlesex and State of Massachusetts, have invented an Improvement in Pile-Wire Knives, of which the following description, in connection with the accompanying drawings, is a specification, like characters on the drawings representing like parts.

This invention relates to a pile-wire knife having novel means providing for the use of blades of uniform size in connection with pile wires of various widths for different classes of work.

The invention will be best understood by reference to the following description when taken in connection with the accompanying drawings of one specific embodiment thereof while its scope will be more particularly pointed out in the appended claims.

In the drawings:

Fig. 1 is an elevation of a pile-wire knife exemplifying the invention;

Fig. 2 is an elevation of the same as viewed from the opposite side thereof;

Fig. 3 is an elevation partly in section illustrating the mode of attaching and detaching the blade;

Fig. 4 is an elevation of the filler which is used as an adapter to adapt the blade to the pile wire;

Fig. 5 is a sectional view on line 5—5 of Fig. 1;

Fig. 6 is a sectional view on line 6—6 of Fig. 1; and

Fig. 7 is a sectional view on line 7—7 of Fig. 3.

Referring to the drawings and to the embodiment of the invention which is selected for exemplification, there is shown a pile-wire knife comprising a blade 8 and a blade holder 9. Herein the blade has a tapered formation, it having a narrow end 10 and a wide end 11. The blade is provided with a cutting edge 12.

The blade holder herein is conveniently formed of sheet metal folded upon itself to provide two walls 13 and 14 between which is a groove 15 to receive the blade. Herein the wall 14 presents a head 16 which is wider than the shank of the holder and this head has a suitably shaped tip or point 17, as is usual with pile wires. The rear end 55 of the blade herein is narrower than the

shank of the holder and is completely concealed by the walls which present the groove for the reception of the blade. The rear end of the blade is retained in the groove by an abutment 18 which overhangs a portion of the blade in such manner that removal of the latter from its normal position represented in Figs. 1 and 2 can be accomplished only by swinging the blade on the abutment as a fulcrum (see Fig. 3). Inasmuch as the fulcrum is at the rear end of the blade this construction may be employed in connection with much narrower wires than that herein shown. In any case the head at the forward end can be made sufficiently wide to carry means to retain the forward end of the blade in the groove in the manner presently to be described.

In the present example the abutment 18 is presented by a strip of metal 19 constituting a filler, which is inserted in the groove 15 between the inner edge of the blade and the bottom of the groove. The fillers used will vary in width in accordance with the various widths of the pile wires, that which is used in a given case being such that the cutting edge of the blade will be presented in the correct relationship with the shank of the wire and with the head,—also in all cases the forward end of the blade is correctly related to the positioning and retaining means presented to be described. The use of the filler therefore makes it unnecessary for the manufacturer or the user to carry in stock blades of various dimensions for use in connection with pile wires of various widths. This results in a great saving as well as in an increased convenience to the manufacturer as well as to the user.

The filler may be fitted so snugly between the walls which embrace it that friction alone may be relied upon to hold the filler in place. If desired, however, the rear end of the filler may be secured in place between the walls, as by forming one or more shallow indentations 20 (one of which is shown in section in Fig. 7) in one of the side walls of the holder, thereby squeezing such wall slightly into the adjacent surface of the filler which is interposed between the walls. It will be remembered that the blade holder is formed of sheet metal folded upon itself. In practice the holder thus formed is usually secured, as by electrically welding the same, to a flat wire 21 of great length. In this

case the welded joint occurs along a line A—A adjacent the rear end of the filler and the latter can be conveniently secured to the holder as well as to the butt end of the 5 wire in the welding operation in which case the indentation or indentations 20 may be omitted.

The forward end of the blade is retained in the groove by the cooperative action of a 10 protuberance 22 presented by the wall 14 and a wall 23 which, in the present example, is conveniently formed as a tongue struck up from the wall 14. The walls 14 and 23 embrace the blade, as best shown in Fig. 5, 15 while the protuberance 22 presents an obstruction to withdrawal of the blade from the groove. The wall 23 is resiliently related to the wall 14, it being in the form of a spring tongue (see Fig. 6) which is adapted 20 to recede from the wall 14 when sufficient pressure is exerted against the blade in its own plane toward the protuberance 22, the latter being rounded or beveled to permit the blade to ride over it. When the blade is in 25 place this tongue resists lateral movement of the blade and accurately positions the latter with reference to the opposite wall irrespective of the width of the groove with 30 reference to the thickness of the blade. This results in accurate cutting of the loops and in uniform appearance of the work. When 35 the blade is in place the tongue 23 constitutes an abutment which defines the position of the blade lengthwise in one direction (see Fig. 6) while the abutment 18 defines its position lengthwise in the opposite direction.

The pile wire and its knife are operated in a manner too well known to those skilled in the art to require description. When the 40 blade becomes dull it may be removed and replaced by a sharp one with the greatest facility and when in place it is securely locked against accidental disengagement from its holder.

Having thus described one embodiment of 45 the invention but without limiting myself thereto what I claim and desire by Letters Patent to secure is:

1. A pile wire knife comprising, in combination, a blade, a blade holder presenting a 50 groove in which said blade is received, and a filler also received in said groove between the inner edge of said blade and the bottom of said groove.

2. A pile wire knife comprising, in combination, a blade, a blade holder presenting a 55 groove in which said blade is received, and a filler also received in said groove between the inner edge of said blade and the bottom of said groove, said filler presenting an 60 abutment for one end of said blade.

3. A pile wire knife comprising, in combination, a blade, a blade holder presenting a 65 groove in which said blade is received, and a filler also received in said groove between the inner edge of said blade and the bottom of said groove, said filler presenting an abutment which overhangs one end of said blade.

4. A pile wire knife comprising, in combination, a blade, a blade holder presenting a 70 groove in which said blade is received, and a filler also received in said groove between the inner edge of said blade and the bottom of said groove, said filler presenting a fulcrum on which said blade may be swung 75 into and out of said groove.

5. A pile wire knife comprising, in combination, a blade, a blade holder presenting a 80 groove in which said blade is received, and a filler also received in said groove between the inner edge of said blade and the bottom of said groove, said filler presenting an abutment which overhangs a portion of said 85 blade and a fulcrum on which said blade may be swung into and out of said groove.

In testimony whereof, I have signed my name to this specification.

DEAN E. LOCHMAN.
